UNITED STATES PATENT OFFICE.

ROSWELL S. JUDSON, OF MATTEAWAN, NEW YORK.

STABLE-FLOOR.

SPECIFICATION forming part of Letters Patent No. 746,094, dated December 8, 1903.

Application filed May 1, 1903. Serial No. 155,174. (No model.)

To all whom it may concern:

Be it known that I, ROSWELL S. JUDSON, a citizen of the United States, residing at Matteawan, in the county of Dutchess and State 5 of New York, have invented certain new and useful Improvements in Stable - Floors, of which the following is a specification.

This invention aims to devise a floor or similar surface support chiefly designed for use 10 in stables and places where horses and stock are kept, being admirably adapted for use in horses' stalls both from a sanitary and humane standpoint, the floor being yieldable to a degree to prevent shock incident to the foot 15 striking down upon a hard unyielding surface.

In accordance with this invention a series 20 of blocks of fibrous material, such as wood, are bound longitudinally and transversely in such a manner as to admit of the resultant floor readily conforming to the surface upon 25 which it may be placed and yielding to pressure or blows from above, so as to neutralize shock and prevent ultimate injury to the animal standing thereon.

For a full description of the invention and the merits thereof and also to acquire a knowledge of the details of construction of the 30 means for effecting the result reference is to be had to the following description and drawings hereto attached.

While the essential and characteristic features of the invention are susceptible of modification, still the preferred embodiment of the 35 invention is illustrated in the accompanying drawings, in which—

Figure 1 is a perspective view of a portion of flooring embodying the invention, same being inverted. Fig. 2 is a top plan view. Figs. 40 3 and 4 are respectively transverse and longitudinal sections of the flooring about on the lines X X and Y Y of Fig. 2. Fig. 5 is a perspective view of a block.

Corresponding and like parts are referred 45 to in the following description and indicated in all the views of the drawings by the same reference characters.

The flooring is composed of a series of blocks 50 1 of any determinate dimensions as to length, breadth, and thickness. These blocks may be of any fibrous material, wood being preferred, and are arranged with their fibers or

grain extending perpendicular or at a right angle to the plane of the flooring. The blocks are preferably square, although this is not essential, and each block is provided with two openings 2 and 3 in different planes and arranged relatively at a right angle, so as to receive the transverse and longitudinal tie-rods 4 and 5. The openings 2 and 3 are slightly 55 larger than the diameter of the tie-rods to admit of relative independent play of the blocks and also lending to the flooring a degree of looseness and flexibility, permitting same to readily conform to the surface upon 60 which the flooring may be placed. The blocks are arranged in transverse and longitudinal parallel lines, the blocks being connected transversely by tie-rods 5, the several tie-rods being passed through the respective 65 transverse and longitudinal openings of the blocks. The tie-rods are headed at one end and are provided at the opposite end with nuts 6. This is not essential, as each end of the tie-rods may be headed or provided with 70 nuts, as found most convenient. The provision of the nuts 6 admits of the position of the blocks being changed, so that worn blocks 75 may be substituted by new blocks or made to change position with other blocks that are not worn. Washers 7 are strung upon the tie-rods and come between adjacent blocks to space them apart to increase the flexibility of the flooring, to provide for ventilation, and to enable fluids to readily pass off. 80

The flooring will involve a sectional construction, the sections being of a size and weight to be conveniently handled by one person, so that the position of the several sections may be changed and the flooring removed from time to time for cleaning. Channels 8 are provided in the lower side of the flooring and communicate with the spaces formed between the blocks, said channels being formed, preferably, by cutting away the 85 lower corners of adjacent blocks. These channels 8 provide for free admission of air and passages for the ready escape of fluids, whereby the floor is at all times dry and in a sanitary condition. 90

Having thus described the invention, what is claimed as new is—

1. Flooring composed of a series of blocks, transverse and longitudinal ties connecting

the blocks in series, and washers strung upon the ties and arranged between adjacent blocks, substantially as set forth.

2. Flooring composed of a series of blocks having transverse and longitudinal openings in different planes, and transverse and longitudinal tie-rods connecting the blocks in series and of less diameter than the opening through which they pass, whereby the blocks are adapted to have a limited independent perpendicular play, substantially as described.

3. Flooring composed of a series of blocks arranged in transverse and longitudinal lines and having transverse and longitudinal openings in different planes, transverse and longitudinal tie-rods connecting the blocks in transverse and longitudinal series, and wash-

ers strung upon the tie-rods and coming between adjacent blocks and spacing the latter, substantially as described.

4. Flooring composed of a series of transverse and longitudinal blocks connected in series by corresponding transverse and longitudinal ties, said blocks being spaced apart, and channels formed in a side of the flooring by cutting away corners of adjacent blocks, substantially as described.

In testimony whereof I affix my signature in presence of two witnesses.

ROSWELL S. JUDSON. [L. S.]
